SPECTACLE FRAME FRONT

Murray Green, New York, N. Y.

Application June 16, 1954, Serial No. 31,020

Term of patent 14 years

(Cl. D57—1)

To all whom it may concern:

Be it known that I, Murray Green, a citizen of the United States of America and a resident of New York city, Borough of Manhattan, county of New York, and State of New York, have invented a new, original, and ornamental Design for a Spectacle Frame Front, of which the following is a specification, reference being had to the accompanying drawing, forming a part thereof.

In this drawing:

Figure 1 is a front elevational view of a spectacle frame front showing my new design; and

Figure 2 is a top plan view thereof; and

Figures 3, 4, 5 and 6 are fragmentary cross-sectional views taken on the lines 3—3, 4—4, 5—5 and 6—6 respectively of Figure 1, at a greatly enlarged scale.

The characteristic feature of my design resides in the

portion attached to the top of the lens holding and bridge portions of the spectacle frame front, which is slightly raised with respect thereto, and contrasts in color with the remaining portions thereof, as indicated by stippling on the drawing.

I claim:

The ornamental design for a spectacle frame front, as shown and described.
